PLATE CLAMP

Darl T. Shank, Dayton, Ohio, assignor to Harris-Intertype Corporation, Cleveland, Ohio, a corporation of Delaware

Filed Feb. 20, 1962, Ser. No. 174,490
7 Claims. (Cl. 101—415.1)

The present invention relates to plate clamps for coating or printing machines, and particularly to a novel 10 plate clamp construction which will rapidly connect the trailing edge of a flexible plate to a cylinder and then tension the plate to hold it immediately adjacent the cylinder.

The invention is concerned primarily, although not 15 exclusively, with apparatus utilized to secure a flexible plate to a cylinder, as for instance, an embossed plate for use in paper coating machines or a lithographic printing plate used in a printing press. In such apparatus it is often desired and many times required that the trailing edge of the flexible plate be tightly clamped to the cylinder in such a manner that there will be no relative movement therebetween. In order to attain this 20 closeness, the plate must be tensioned and it is desirable to apply this tension in conjunction with the clamping apparatus. Of particular importance is the requirement that such apparatus be simple in design for maximum dependability and that it be easily actuated preferably by simple manual movements so that the plate can be 25 properly secured to the cylinder with a minimum of time and effort.

Accordingly, a particular object of this invention is to provide apparatus for securely clamping a flexible plate to a cylinder including a clamp which will positively lock the flexible plate to the cylinder in response 30 to a manual actuation while being easily and quickly releasable.

Another object of the invention is to provide apparatus for securely clamping a flexible member to a cylinder and applying tensioning to the plate to hold the same close to the cylinder which requires only simple 35 manual movements to clamp and tension the plate, as well as release this tension and unclamp the plate.

A further object of the invention is to provide a 40 clamping and tensioning apparatus for securely holding the trailing edge of a flexible plate on a cylinder wherein the apparatus is capable of being sequentially operated to first clamp the plate and then apply tension thereto or to untension the plate and then unclamp the same which apparatus is simple in design for ultimate 45 dependability and ease and speed of operation.

In the drawings—

FIG. 1 is a schematic end view of a cylinder utilizing the invention to clamp a plate thereon;

FIG. 2 is a fragmentary plan view of a clamp built according to the invention;

FIG. 3 is a sectional view taken essentially along the line 3—3 of FIG. 2;

FIG. 4 is a fragmentary illustration, partially in section, showing an end clamp;

FIG. 5 is a similar sectional view taken essentially along the line 5—5 of FIG. 2;

FIG. 6 is a sectional view similar to that of FIG. 4 but showing the cams in an alternate position;

2

FIG. 7 is a sectional view similar to FIG. 3 but illustrating the cam and clamp means in an alternate position;

FIG. 8 is a sectional view essentially along the line 8—8 of FIG. 2;

FIG. 9 is a sectional view similar to that of FIG. 7 and illustrating the cam means in an alternate position;

FIG. 10 is a sectional view essentially along the line 10—10 of FIG. 2; and

FIG. 11 is a sectional view essentially along the line 11—11 of FIG. 2.

Referring to the drawings which illustrate a preferred embodiment of the invention, FIG. 1 shows diagrammatically a cylinder 10 similar to those utilized on a coating machine, printing press or the like and having an embossing or printing plate 11 of a flexible material secured thereto. The leading edge 13 of the plate 11 is rigidly clamped between the members 15—16 by the bolts 17 after the plate 11 has been manually aligned therebetween. The trailing edge 18 of the plate 11 is releasably clamped in a novel plate clamp 20 which, in addition to clamping the trailing edge 18, tensions the plate properly on the cylinder 10.

As shown in FIGS. 2 and 3 the plate clamp 20 includes the elongated supporting bar or base plate 21 which is mounted for certain relative movements in the recess 23 cut in the cylinder 10, but held against movement in a radial direction with respect to the cylinder 10 by end pieces 25 which are secured to cylinder 11 at each end of the base plate 21 by the bolts 27 and which have a flange 28 which extends over the end of the plate 21. A bore or recess 30 in the base plate 21 holds the spring 31 which rides flange 28 to hold the plate against any significant radial movement with respect to the cylinder 10 while permitting it to move within limits toward and away from the shoulder 32 of recess 23. In addition, limited axial movement of the plate 21 with respect to the cylinder 10 is accomplished and controlled by a screw member 33 threaded through each end clamp 25 for engagement with the end of the plate 21. By retracting the screw 33 on one end of the plate 21 and tightening the screw on the other end the plate 21 can be moved axially on the cylinder 10.

The apparatus utilized to clamp the edge 18 of the flexible plate 11 to the support plate 21, as shown in FIG. 3, includes an elongated clamp bar 35 which is substantially coextensive with the plate 21, save the clearance provided for the end clamps 25. A plurality of spaced pivot bolts 36 having semi-spherical heads 37 are inserted through the openings 39 in the clamp bar 35 and screwed into the threaded bores 40 of the support plate 21 thereby pivotally securing this clamp bar 35 on plate 21.

The surfaces of the openings 39 and the spherical heads 37 are similarly shaped so that the clamp bar 35 will pivot about the heads 37 between the positions shown in FIGS. 3 and 7. The bolts 36 can be screwed into or out of the plate 21 to permit the effective pivot point of bar 35 to be raised or lowered to compensate for the varying thickness of the plate 11, so that the clamping surface 41 will fit flat against the plate 11. After the proper adjustments are made each of the bolts 36 is locked into position by a pin 42 which is forced thereagainst by rotating the threaded plug 43 in the similarly threaded bore 44 of the

support plate 21. The clamping surface 41 which engages the edge 18 of plate 11 is knurled so that it is held against slippage, and the opposite side of the clamp bar 35 includes a cam follower portion 47 engaging the cam bar 50 which is coextensive with clamp bar 35.

A coil spring 51 is placed in each of the longitudinally spaced recesses 52, see FIGS. 2 and 5, in such a manner that the springs tend to move the clamp bar 35 about the pivot bolt 36 to relieve any pressure exerted by the surface 41 on the edge 18 of plate 11. On the other hand, the clamp bar 35 may be pivoted against the bias of these springs 51 to a clamping position by the cam bar 50 which is rotatably journaled in bearings 53 and rides in a groove 54 formed in the support plate 21. FIG. 7 illustrates the cam bar 50 moved to an inactive position wherein the spring 51 has rotated the clamp bar 35 in a clockwise direction to release the clamping pressure on the edge 18 of the flexible plate 11. Further counterclockwise rotation of cam bar 50 from this position is prohibited by the ear 55 formed thereon.

A cam actuator block 56 utilized to rotate cam bar 50 is rigidly secured thereto by the pins 57 at a position midway between the ends of the assembly and both the clamp bar 35 and the support plate 21 are cut out at 58 (see FIGS. 2 and 8) in order that this block 56 may rotate freely and to provide surfaces on which the bearings 53 are mounted by the bolts 59.

The apparatus for tensioning the plate 11 on the cylinder 10 once it has been clamped to the support bar 21 includes a spring means shown in FIG. 10 and a manually actuated means shown in FIG. 11 both of which move the support plate 21 away from shoulders 32 (to the right as viewed in FIG. 1). The spring means include a coil spring 60 interposed between the disk 62 mounted in the recess 63 of the support plate 21 and the shoulder 32 for urging the plate 21 to the right thereby tensioning the flexible plate 11 when the latter is clamped thereto. The force exerted by spring 60 can be varied within certain limits by the threaded plug 65 which engages the similarly threaded bore 67 in the plate 21. On the other hand, each of the manually actuated tensioning means shown in FIG. 11 includes a manually adjustable pin 70 slidably mounted in a bore 71 of the plate 21. Pin 70 is forced against the shoulder 32 of the cylinder 10 by rotation of the threaded bolt 73 which engages similarly threaded bore 74. The bolt 73 has an enlarged head 75 with radial openings 77 therein for insertion of a tool or bar to facilitate the rotation thereof and a lock nut 78 is provided for locking the bolt 73 in position. It should be appreciated that this tensioning means is of the positive type whereas the spring tensioning means of FIG. 10 merely provides tensioning in an amount equal to the biasing effect of the springs 63.

A tensioning cam 80 is rigidly held on the cam bar 50 on either side of the actuator block 56 by pins 81 and acts against the stationary blocks 82 secured to cylinder 10 by the bolts 83. The cam 80 has an annular extension 84-85 and formed integrally therewith on either side thereof. As shown, one of these extensions 84 accommodates the pin 81 to secure the cam to the bar 50 while the other extension 85 engages the bearing 53 to support both the cam 80 and cam bar 50. As shown in FIG. 5 rotation of the tensioning cam 80 effects movement of the support plate 21 toward the shoulder 32 to a position wherein this tension is released, that is, to an active position wherein the plate 21 is moved toward the left against the bias of the spring 60 thereby relieving the tension on the plate 11. Naturally, if the positive tensioning means of FIG. 11 is engaged it must be retracted before the cam 80 can move the support plate 21 to the left for relieving this tension. FIG. 6 shows the tensioning cam 80 rotated to an inactive position wherein it no longer engages the block 82 and the spring 60 of the positive tensioning means of FIG. 11 are free to apply tension to the plate 11. Hence, it should be apparent

that the primary purpose of the tensioning cam 80 is to relieve the tensioning being applied to the plate 11 by the spring 60 and to move the plate 21 toward the shoulder 32.

5 Since the tensioning cam 80 and the cam bar 50 are rigidly interconnected and hence rotate together their relative angular position must be precisely established before they are interconnected to insure proper operation of the invention. This precise positioning permits 10 a highly desirable sequence of operations to take place, and can best be explained by setting forth the sequence of operations. Starting with the cam bar 50 in the position shown in FIG. 7 wherein spring 60 pivots the clamp bar 35 to its released position, clockwise rotation of cam 15 bar 50 will clamp the edge 17 of the plate 11 to the support plate 21 thereby pivoting the clamp bar 35 against the bias of spring 60 to the position shown in FIG. 5, wherein the plate 11 is securely clamped to the plate 21. Further clockwise rotation of the cam bar 50 then moves the tensioning cam 80 from the active 20 position shown in FIG. 5 to the inactive position shown in FIG. 6 wherein the cam 80 is spaced from the block 82 and tensioning is applied to the plate 11 by the spring 60 or the positive means shown in FIG. 11. The tensioning and clamping of the plate 11 is relieved by rotating 25 the bar 35 in a counterclockwise direction from the position shown in FIG. 5. It should be apparent from the foregoing that the cam bar 50 and the tension cam 80 are so shaped that tensioning will never be applied unless 30 the plate 11 is first clamped to the support plate 21. The clamp bar 35 cannot release the plate 11 unless the tension applied thereto has been previously relieved.

35 Rotation of the cam bar 50 is accomplished by inserting an appropriate tool 87 into one of the two angularly spaced holes 88 and 89 (FIGS. 8-9) in the block 56 to thereby rotate the same. These holes are angularly spaced so that when the system is mounted in its operative environment a tool inserted in the hole 88 will rotate the block 56 only a sufficient amount to rotate the cam bar 50 between the positions shown in FIGS. 5 and 7 whereas when the tool is withdrawn from the hole 88 and inserted in the other hole 87 the cam bar 50 can be rotated between the positions shown in FIGS. 5 and 6. The limits on the movement of the tool are imposed by 40 the clearance between the tool and the machinery associated with the plate clamp. The dual set of holes therefore conveniently limit the movement of tool 87 to thereby separate the clamping and tensioning phases of the mechanism. While this is the preferred manner of applying rotation to the cam bar 50 and the tension cam 80, it is within the contemplation of the invention that other and structurally different expedients can be utilized. For example, the cam 50 could be extended past the 45 end clamp 25 and a suitable configuration formed on this end for gripping with an appropriate tool.

50 While the invention has been shown and described in connection with a cylinder used in coating machinery or a printing press, it should be understood that it may find use in other environment without departing from the scope of the invention. For example, the novel plate clamp 55 could be utilized to clamp and tension flexible or semi-flexible members on a flat surface. The amount of tensioning can be varied by merely altering the apparatus to provide for more or less movement of the plate 21 toward and away from the shoulder 32 as well as by changing 60 the bias of spring.

65 While the methods herein described constitute preferred embodiments of the invention, it is to be understood that the invention is not limited to these precise methods, and that changes may be made therein without departing from the scope of the invention which is defined in the appended claims.

70 What is claimed is:

75 1. A plate clamp for releasably securing and tensioning a flexible member on a mounting surface, comprising

an elongated support plate mounted for limited movement with respect to said surface, clamping means mounted on said plate and movable to a first position for cooperation with said plate in clamping one end of the member to said plate and also movable to a second position releasing the one end of the member, first spring means urging said clamping means forward to said second position, a first cam means operable on said clamping means and movable between an active position holding said clamping means in said first position and an inactive position wherein said first spring means moves said clamping means to its said second position, second spring means urging said plate toward a tensioning position for applying tension to the member, second cam means operable on said plate and movable to one position to move said plate against said second spring means for relieving tension in the member, said second cam means also being movable to an opposite position causing said second spring means to tension the member, and singular cam actuator means operable to move said first cam means to its said active position and then to move said second cam means to its said opposite position.

2. A plate clamp for releasably securing and tensioning a flexible member on a mounting surface, comprising an elongated support plate mounted for limited movement with respect to said surface, clamping means mounted on said plate and movable to a first position for cooperation with said plate in clamping one end of the member to said plate and also movable to a second position releasing the one end of the member, first spring means urging said clamping means forward to said second position, a first cam means operable on said clamping means and movable between an active position holding said clamping means in said first position and an inactive position wherein said first spring means moves said clamping means to its said second position, second spring means urging said plate toward a tensioning position for applying tension to said member, second cam means operable on said plate and movable to one position to move said plate against said second spring means for relieving tension in the member, said second cam means also being movable to an opposite position causing said second spring means to tension the member, and a cam actuator for sequentially moving said first cam means to its said active position and then moving said second cam means to its said opposite position and then moving said second cam means to said one position and then moving said first cam means to said inactive position.

3. A plate clamp for releasably securing and tensioning a flexible member on a mounting surface comprising an elongated support plate mounted for limited movement with respect to said surface, clamping means mounted on said plate and movable to a first position for cooperation with said plate in clamping one end of the member to said plate and also movable to a second position releasing the one end of the member, first spring means urging said clamping means forward to said second position, a first cam means operable on said clamping means and movable between an active position holding said clamping means in said first position and an inactive position wherein said first spring means moves said clamping means to its said second position for moving said plate to a tensioning position for applying tension to the member, second cam means connected to move said plate against said second spring means to relieve tension in the member, said second cam means also being movable to an opposite position causing said second spring means to tension the member, and singular cam actuator means operable to move said first cam means to its said active position and then to move said second cam means to its said opposite position.

4. A plate clamp for releasably securing and tensioning a flexible member on a mounting surface, comprising an elongated support plate mounted for limited movement with respect to said surface, clamping means mounted on said plate and movable to a first position for cooperation

with said plate in clamping one end of the member to said plate and also movable to a second position releasing the one end of the member, first spring means urging said clamping means to said second position, a cam bar operable on said clamping means and movable between an active position holding said clamping means in said first position and an inactive position wherein said first spring means moves said clamping means to its said second position, second spring means urging said plate toward a tensioning position for applying tension to the member, a tensioning cam operable to move said plate against said second spring means to relieve tension in the member, said tensioning cam also being movable to an opposite position causing said second spring means to tension the member, said cam bar and said tensioning cam being operably interconnected in angularly offset relation for positioning said cam bar in said active position before said tensioning cam is moved to said inactive position.

5. A plate clamp for securing releasably one end of a flexible member to a support surface and for applying tensioning to the member, comprising an elongated support plate mounted for movement with respect to said surface, clamping means substantially coextensive with said support plate and mounted thereon for pivotal movement between a clamping position wherein said clamping means cooperates with said plate to clamp the one end of the flexible member therebetween and an unclamping position wherein said clamping means releases the one end, a cam bar mounted on said support plate for movement between an active position wherein said clamping means is moved to said clamping position and an inactive position wherein said clamping means is moved to said unclamping position, a tensioning cam operable to move said support plate between one position wherein tension is applied to said member and an opposite position wherein said tension is relieved, said cam bar and said tensioning cam being secured together in angularly offset relation for positioning said cam bar in said active position when said tensioning cam is in said opposite position.

6. A plate clamp for releasably securing and tensioning a flexible member on a mounting surface, comprising an elongated support plate mounted for limited movement with respect to said surface, clamping means substantially coextensive with and mounted on said plate and movable to a first position for cooperation with said plate in clamping one end of the member to said plate and also movable to a second position releasing the one end of the member, spring means for moving said clamping means to said second position, a cam bar mounted on and substantially coextensive with said plate and movable between an active position holding said clamping means in said first position and an inactive position wherein said spring means moves said clamping means to its said second position, first means for moving said plate toward a tensioning position for applying tension to the member, a tensioning cam rigidly mounted on said cam bar in angularly offset relation for moving said plate to relieve tension in the member and also for movement to an opposite position for permitting said first means to move said plate to said tensioning position, and cam actuator means connected to said cam bar for moving said cam bar to its said active position and then moving said tensioning cam to its said opposite position.

7. A plate clamp for releasably securing and tensioning a flexible member on a mounting surface, comprising an elongated support plate mounted for limited movement with respect to said surface, clamping means substantially coextensive with and mounted on said plate and movable to a first position for cooperation with said plate in clamping one end of the member to said plate and also movable to a second position, releasing the one end of the member, spring means for moving said clamping means to said second position, a cam bar mounted on and substantially coextensive with said plate and movable between an active position holding said clamping means

in said first position and an inactive position wherein said spring means moves said clamping means to its said second position, first means for moving said plate toward a tensioning position for applying tension to the member, a tensioning cam pivotable to one position for moving said plate to relieve tension in the member, said tensioning cam also being movable to an opposite position for causing said spring means to tension the member, said tensioning cam being rigidly mounted in angularly offset relation on said cam bar for moving said tensioning cam 10

to and from its said opposite position only when said cam bar is in said active position, and cam actuator means for moving said cam bar.
